UNITED STATES PATENT OFFICE.

JULIAN ALBERT CRANE, OF Vining, KANSAS.

PROTECTOR FOR CARPETS, CURTAINS, &c.

SPECIFICATION forming part of Letters Patent No. 396,327, dated January 15, 1889.

Application filed March 19, 1888. Serial No. 267,724. (No model.)

To all whom it may concern:

Be it known that I, JULIAN ALBERT CRANE, a citizen of the United States, residing at Vining, in the county of Clay and State of Kansas, have invented certain new and useful Improvements in Curtain, Carpet, and Wall-Paper Protectors; and I do hereby declare that the following is a full, clear, and exact description of the invention, which will enable others skilled in the art to which it appertains to make and use the same, reference being had to the accompanying drawings, which form a part of this specification, and in which—

Figure 1 is a top perspective view of my new and improved protector for carpets, lace or other curtains, and wall-paper, the device being shown constructed in such a manner as to fit snugly upon the window-ledge and against the sides of the window-easing. Fig. 2 is a similar view of my device, with the exception of a slight change in its construction, the object of which will be hereinafter set forth. Fig. 3 is a longitudinal sectional view of the device removed from the window, taken through the inclined recess or groove. Fig. 4 is a cross-section taken through that end of the device to which the cup or receptacle is secured, and Fig. 5 is a perspective view of the protector detached.

Similar letters of reference denote corresponding parts in all the figures.

My invention has relation to that class of devices for preventing the water or moisture that collects upon the interior of the window during cold weather and runs down to the bottom of the sash as soon as it melts from dripping off of the window-ledge onto the carpet, the wall-paper below the window, or onto the curtains which have been drawn down below the window-ledge; and to this end my improvement consists in the improved construction of such a device whereby these drawbacks are overcome.

In the accompanying drawings, the letter A denotes the window-easing, consisting of the side pieces, B, and the lower connecting-piece, C; D, the window-sash, and E the window-ledge, all of which are of the usual and well-known construction.

F indicates the protector, which consists of a flat board provided with a longitudinal groove or recess near its inner edge. This

groove or recess G inclines or deepens toward one end, and opens into or communicates with an aperture, H, beneath which is an exteriorly-screw-threaded hollow tenon, I, open at its lower end and provided at its upper end with a flange or collar, J, which is secured by means of screws, nails, or other suitable fastening devices to the under side of the board. 55

K denotes the can or receptacle, the mouth of which, M, is provided with the interiorly-screw-threaded socket L, which is soldered or suitably secured to the top of the can or receptacle. 60

N indicates the short grooves or recesses formed in the board at right angles to the longitudinal groove and incline downwardly until they intersect the longitudinal groove. 65

O indicates the set-screws employed for securing the protector to the window-ledge when the protector is constructed with the shoulder P and the extension Q, as shown in Fig. 1 of the drawings. This construction is obvious, and it is thought will not need further explanation, as it will naturally suggest itself to an ordinary mechanic. 70

If desired, the protector can be formed in the sill or ledge of the window when the easing is made, by simply cutting the long inclined groove G and shorter transverse grooves N in the same manner as where the protector is made separate, as shown in Fig. 2. In this construction the can is secured beneath the hole H in the sill in the same 75 manner as above described.

It will be seen that while in either position the water or moisture that collects and runs down the window enters the short grooves or recesses and is conducted into the longitudinal groove, whence it is conducted to its apertured end, and thence through the aperture into the can or receptacle. This can, after having become filled, can be removed by unscrewing it and its contents discharged, when 80 it is then secured in position. Thus it will be seen that the carpet, curtains, and wall-paper are prevented from getting wet or becoming ruined, and a considerable amount of time is saved for the housekeeper. 85

From the foregoing description, taken in connection with the accompanying drawings, the operation and advantages of my invention will be readily understood without re- 90 100

quiring extended explanation. It will be seen that it is simple and strong in construction, durable in usage, and can be readily attached to or detached from a window in a short space 5 of time, while it can be manufactured and sold at such a low figure as to place it within the reach of all classes.

Having thus described my invention, I claim and desire to secure by Letters Patent of the 10 United States—

A protector for carpets, curtains, and like articles, adapted to be secured to the lower portion of a window - frame, consisting of a board formed with a longitudinal groove communicating with an aperture, and with short 15 grooves intersecting the longitudinal groove at right angles, in combination with a can or

receptacle, a hollow exteriorly-screw-threaded tenon open at its lower end and provided with a flange or collar at its upper end, by means 20 of which it is secured by screws or other suitable fastening devices to the under side of the board and registering with the said aperture, and an interiorly - screw - threaded socket secured upon the top of the can or receptacle 25 and encircling the aperture therein, substantially as set forth.

In testimony that I claim the foregoing as my own I have hereunto affixed my signature in presence of two witnesses.

JULIAN ALBERT CRANE.
